MACHINE FOR SLUSHING SHEETS OF PULP

William T. Doyle, Boston, Thomas J. Sturtevant, Wellesley, and Laurance H. Sturtevant, Quincy, Mass., assignors to Sturtevant Mill Company, Boston, Mass., a corporation of Massachusetts

Application June 26, 1934, Serial No. 732,454

11 Claims.

(Cl. 92—20)

This invention relates to a machine for slushing sheets of pulp in water to produce an aqueous pulp suspension intended for such purposes as papermaking. It deals more particularly with an improved machine of the type disclosed in Doyle Patent No. 1,910,382, dated May 23, 1933, wherein the improvements generally include accurate guiding and more positive feeding of a succession of sheets in the form of bales to a rotary hammer mill wherein they are reduced in the presence of water to form the aqueous pulp suspension, more positive intake of the successive sheets one by one into the mill, adjustability of parts for sheets of different sizes, better accessibility to and easier replaceability of internal parts of the mill, and ready controllability of the volume of water supplied to the sheets so as to permit of the production of an aqueous pulp suspension of the desired stock density or consistency.

With the foregoing and other improvements and objects in view, the present invention will now be described in greater detail with reference to the accompanying drawings, wherein—

Figure 1 represents a side elevation of the machine as a whole.

Figure 2 represents a rear end elevation of the machine.

Figure 3 is a longitudinal section on the line 3—3 of Figure 2.

Figure 4 is an enlarged transverse section through the rotary hammer mill and parts adjacent thereto.

Figure 5 is an enlarged plan section on the line 5—5 of Figure 4.

Figure 6 is an enlarged fragmentary section through a section of the mill casing on the line 6—6 of Figure 4, the lining of the casing being removed for the sake of clarity.

Figure 7 represents an enlarged side elevation of a guide partition for the bales of sheets as they are being fed to the hammer mill.

Figure 8 is a section on the line 8—8 of Figure 7.

Figure 9 represents an enlarged side elevation of that part of the hammer mill housing at which the water-control means is located.

Figure 10 is a section on the line 10—10 of Figure 9.

Figure 11 is a section on the line 11—11 of Figure 10.

Figure 12 is a plan view of the hammer mill rotor, some of the hammers being omitted for the sake of clarity.

Figure 13 depicts a development of a preferred hammer mill rotor so as to show the relative po-

sitions of the various hammer elements on the rotor.

Referring now to Figure 1 of the drawings, 10 represents an endless conveyor arranged to move at a slight incline to the horizontal and onto which the bales of pulp sheets may be deposited with the sheets in upstanding relationship. As shown, a whole bale 11 may be transferred to the conveyor by suitable tongs 12 forming part of hoisting mechanism (not shown). The conveyor 10 comprises a plurality of chains passing over end sprockets 13, the lower sprocket of which may be driven as will presently be described. The conveyor 10 may comprise two spaced chains, each chain of which passes over the sprockets 13 and between the links of which may extend transversely a plurality of slats (not shown) presenting flat upper faces on which the bales 11 rest. Immediately below the upper stretch of the conveyor 10 is, as best shown in Figure 3, preferably provided a supporting table 14 which serves to prevent sagging of the conveyor under load. Adjacent to the side edges of the conveyor 10 are also preferably provided guide rails 15 which define a runway of progressively diminishing width toward the lower end of the conveyor, wherefore, no particular attention need be given to the placement of the bales on the conveyor, since the bales are properly guided by the rails to the lower or discharge end of the conveyor.

The conveyor 10, which is the primary one, delivers the bales onto a secondary conveyor 16 which serves to carry the bales into the intake of the hammer mill. The secondary conveyor 16 also moves at a slight angle to the horizontal but the upper end of its upper stretch is slightly below the lower end of the upper stretch of the primary conveyor 10 so that the bales will drop slightly as they are discharged from the primary conveyor onto the secondary one. In order that the bales 11 may be positively and uniformly fed into the intake of the hammer mill, the links of the chains comprising the secondary conveyor are preferably provided with teeth or spikes 17 which, under the weight of the bales, tend to bite into the bales 11 as they drop from the primary conveyor onto the secondary one. The chains comprising the secondary conveyor pass over end sprockets 18, the lower one of which is driven as will presently be described. The upper stretch of the secondary conveyor is also preferably kept from sagging under load by a supporting table 19 located immediately thereunder. The drive for both conveyors may include a motor 20 which, through a belt 21, drives a pulley 22, whose shaft is geared

to suitable gear-reducing mechanism in a box 23 from which the desired motive power may be transmitted through a chain 24 to the shaft of the lower sprocket 13 of the primary conveyor 5 and through a chain 25 to the shaft of the lower sprocket 18 of the secondary conveyor. For smooth and efficient operation of the machine, it is necessary that the bales be in close contacting relationship and thus enter as a continuous 10 succession of sheets into the hammer mill. Accordingly, the primary conveyor is driven at a slightly greater rate of speed than the secondary conveyor, any space left between two bales deposited on the first conveyor being eliminated before they reach the secondary slower moving conveyor which is constantly kept fully loaded with bales, as shown in Figure 1. No difficulty is had 15 in discharging the bales from the primary conveyor onto the secondary one by reason of the smooth supporting surface presented by the primary conveyor, the primary conveyor simply slipping under the bales as they drop therefrom onto the spiked supporting surface of the secondary conveyor.

25 As the bales are being fed into the intake of the hammer mill, they are kept from lateral displacement by guide partitions 26 upstanding at the sides of the secondary conveyor and secured to the frame 27 defining the intake of the hammer mill. In order that bales of various widths may be held in proper alignment for feeding into the intake of the hammer mill, the partitions 26 are secured by bolts 28 to the frame 27, the shanks of the bolts passing through slots 29 in a flange portion 27a of the frame 27, wherefore, when the bolts are loosened, lateral adjustment of the partitions 26 is possible. The partitions 26 include flange portions 26a which are normally held by the bolts 28 in abutting relationship with the flange portion 27a of the frame 27.

40 It is desirable to stop the sheets constituting the bales from falling into the hammer mill when running of the machine is stopped, as this makes for restarting of the rotor of the hammer mill under light load. Otherwise, difficulty might be had in restarting the rotor of the hammer mill, since the load or resistance imposed by sheets present therein is a heavy one. To this end, suitable stops for the sheets may be placed in their path when running of the hammer mill is to be stopped. As best shown in Figures 7 and 8, the stops for the sheets are put into play by the operator from outside the partitions 26. The sheet-stopping mechanism shown in these figures includes a bell crank lever operating in a vertical plane and comprising a weighted horizontal operating arm 30 and a vertical arm 31 pivotally secured to a bracket 32 on the outside of the partition 26. Fastened to the vertical arm 31 through a link 33 is a bell crank lever operating in a horizontal plane and comprising a transversely extending arm 34 and a longitudinally extending arm 35 entering into the intake of the hammer mill. The arms 34 and 35 are pivotally secured to a bracket 36 located on the outside of the corner defined by the partition 26 and its flange portion 26a, the arm 35 passing through a slot formed in the flange portion 26a. The inner end of the arm 35 takes the form of an inclined sharp edge blade 35a, its angle of inclination being such that it can be dug readily into the bales and thus arrest the progress of the oncoming succession of sheets. The desired stoppage of the sheets may be had by moving outwardly a weight 36 slidably supported on the arm 30, the

effect of which movement is to cause the blade 35a to move transversely inwardly, as indicated in dotted outline in Figure 8, into the path of the oncoming succession of sheets and thus to arrest their progress.

5 The bales are forced from the lower end of the secondary conveyor onto a shelf 37 constituting the bottom of the hammer mill intake. The top of the hammer mill intake is afforded by a plate 38 secured to a vertically adjustable beam 39. 10 Aside from the possible function of the plate 38 in bearing down upon and sealing, if desired, the tops of the bales, it serves as a breaker plate for the sheets or sheet fragments, its inner edge 38a being sharp and determining the size of stock 15 particle or fragment that can be swept or carried freely past such edge into the hammer mill casing. By providing a proper clearance between the inner edge 38a and the rotor of the hammer mill it is possible to control the size of stock particles or fragments being carried into the casing 20 so as to ensure smooth running action of the rotor. The amount of stock entering into the hammer mill is necessarily determined by the rate at which the sheets are being fed by the conveyors, but the plate 38 determines the extent 25 to which the stock must be comminuted or disintegrated before it can escape past the inner edge 38a into the casing of the hammer mill wherein disintegration of the stock is completed to produce 30 the desired kind of aqueous pulp suspension. The desired clearance between the inner edge 38a and the rotor of the hammer mill may be had by a vertical adjustment of the beam 39 to which the plate 38 is secured as by bolts 40. The adjust- 35 means shown for this purpose includes, as best shown in Figures 2 and 4, a pair of worms on a worm shaft 41, each worm of which meshes with a worm gear 42 on a vertical shaft 43 whose lower end portion 43a is in threaded engagement 40 with a nut 44 secured to the upper face of the beam 38. The beam 39 is vertically slidable in suitable ways 45 in the frame 27. A suitable bracket 46 affording the necessary bearings for the worm shaft 41 and the shaft 43 may be secured 45 to the upper face of a girder 45, which, as best shown in Figure 4, forms part of the housing for the hammer mill. It is thus seen that by affixing a removable hand-wheel 47, shown in dotted outline in Figure 1, to an end of the worm shaft 41 50 and turning it, it is possible to effect a raising or lowering of the beam 39 and the desired adjustment of the breaker plate 38.

55 The hammer mill casing includes an arcuate section 48 equipped with a transversely ribbed lining 49 serving as the brushing plate against which the stock is disintegrated and abraded as it passes through the mill. Located at the front edge of the section 48 is shown a plate 50 which functions to supplement the action of the inner 60 edge 38a of the plate 38 in that it determines the extent to which the stock must be disintegrated before it proceeds into the brushing zone of the hammer mill casing. The plate 38 may thus be considered as the primary breaker plate against 65 which the stock must be preliminarily disintegrated before it can enter into the hammer mill casing; and the plate 50 constitutes a secondary breaker plate which ensures the desired disintegration of the stock before it proceeds into the 70 brushing zone of the hammer mill casing. Once the stock has entered into the brushing zone of the hammer mill casing, it undergoes the brushing action of the hammers as they sweep past the ribs of the lining 49, the hammers either 75

striking against such ribs or barely clearing them. As best shown in Figure 6, each end edge 48a of the arcuate casing section 48 is turned downwardly and rests on a ledge 51 afforded by each end 52 of the hammer mill casing. In this latter figure, the ribbed lining 49 for the section 48 is omitted for the sake of clarity. The section 48 is fixed in place on the ledge 51 and against a flanged portion 55 of the girder 45 by bolts 56 which are in threaded engagement with and pass through suitable bearing members 57 bolted to the top 58 of the hammer mill housing and whose lower ends engage the upper faces of lugs 59 protruding from the upper face of the casing section 48. The lugs 59 present inclined upper faces and the bolts 56 are arranged at an angle of inclination opposite to that of such faces, with the result that the lower ends of the bolts engage the inclined faces of the lugs so as to create a wedging action which forces the section 48 into tight engagement with the flange 55.

The hammer mill casing is further defined beyond the brushing zone by a foraminous arcuate section 60 which constitutes the discharge section of the hammer mill casing and also rests on the ledge 51. The discharge openings in this section may be perforations of circular or other form; or they may be slots running transversely of the section. Inasmuch as this section tends to become worn in service and must be renewed, provision is made for permitting a quick removal of this section from outside the hammer mill housing. It is thus further possible to renew this section without working with tools inside the hammer mill casing, thereby eliminating the possibility of tools or other parts being left in the hammer mill with possible serious damage thereto. As best shown in Figure 4, the section 60 is equipped with a flange 61 at its upper edge and a flange 62 at its lower edge. The flange 61 is abutted and fixed against a flange member 63 suitably secured to the section 48. The desired fixation is realized by a blade 64 having a bevelled inner edge 64a which may be made to exert pressure against the flange 61. The pressure desired on the blade 64 may be derived from a pair of pins 65 each of which passes through a side wall 52 of the hammer mill housing and which is constructed to exert a wedge action against the blade 64. As shown, the desired wedge action is realized by engaging an outer edge portion 64b of the blade 64 within a tapered slot formed in the pin 65, the edge of the portion 64b and the inner wall of the slot mating and being wedge-shaped so that when pressure is exerted inwardly on the pin 65, the blade 64 moves inwardly so as to exert pressure against the flange 61. The desired inward pressure on the pin 65 may be had from a bearing plate 67 engaging over the outer end of the pin 65 and held in place by nuts 68 threaded onto studs 69 affixed to the housing wall 66. It is thus seen that as the nuts 68 are tightened on the studs 69, the blades 64 are caused to bring fixing pressure to bear on the flange 61 and further that as the nuts 68 are loosened and a retraction of the pins 65 is effected, the flange 61 is no longer fixed to the flange member 63 and the discharge section 60 is loose for removal at its upper edge. The flange 62 at the lower edge of the discharge section 60 is abutted and fixed against an outer edge 70 of a trough 71 whose function will presently be described. Such fixation is effected by a blade 72 having a bevelled inner edge 72a. The blade is held in a pair of jaws 73, each of which constitutes a bell-crank

lever pivotally secured to a bracket 74 projecting from a wall of the trough 71. The desired inward movement of the blade 72 so as to fix the flange 62 in position is had by pivotally securing the lower end of the lever 73 to a rod 75 which passes through a bearing 76 projecting from the lower end wall 77 of the housing. The outer end portion of the rod 75 is in threaded engagement with a hand-wheel 78 whose inner end bears against the bearing 76. By tightening the hand-wheels 78 against the bearing 76, the levers 73 are thus caused to force the blade 72 inwardly so as to fix the flange 62 in position, whereas by loosening the hand-wheels 78, a retraction of the blade 72 results, so that the discharge section 60 is loose for removal at its lower edge. It is thus seen that instrumentalities outside of the hammer mill housing make possible the removal of the discharge section 60 and that when such removal has been accomplished, it becomes possible to remove the section 48 of the casing. The removal of the discharge section 60 may be accomplished through the rear end wall of the housing by constructing the end wall 78 of the housing in the form of a door hingedly secured as at 80 and normally locked in place by suitable locks 81, as shown in Figure 2. The section 48 may be removed through the top of the housing by constructing the top 58 of the housing in the form of a removable plate or cover, as shown in Figure 4. The sheets of pulp constituting the bales are wet with sufficient water as they are being fed into the hammer mill casing to ensure the desired pulping or slushing action and to produce a pulp suspension of the desired density or stock consistency. The water necessary for this purpose is fed under pressure from a suitable source (not shown) through a pipe 82 and thence into a header 85, some of the water from the header being diverted through a valve 83 and a pipe 86 leading to the trough 71. The header 85 may form part of the shelf or bottom 37 of the intake of the hammer mill, as best shown in Figure 4. From the header 85, the water passes to two spray pipes located adjacent to the top of the intake and a spray pipe located immediately beyond the bottom of the intake. Thus, the flow takes place from the header 85 upwardly through a pipe 87 (see Figure 1) having two branches at its upper end, one branch being a flexible hose 88 leading by way of a pipe 89 to a spray pipe 90 located immediately in front of the first breaker plate 38. The spray emanating from the pipe 90 wets down the bale wrappers and the sheets of pulp sufficiently before disintegrating action takes place to permit thorough preliminary soaking of such wrappers and sheets. The other branch 91 of the pipe 87 leads to a spray pipe 92 located in a clearance space between the first breaker plate 38 and the second breaker plate 50, the spray emanating from the pipe 92 being directed in the direction indicated by the arrow so as to saturate with water such chunks of pulp as are being held back by the breaker plates, thereby promoting the disintegration of such chunks so that they may be swept into the hammer mill casing. Most of the water for slushing the sheets and for producing a suspension of the desired consistency is delivered from the header 85 by way of a pipe 93 to a spray pipe 94 located immediately beyond the bottom 37 of the intake. The spray emanating from the pipe 94 takes two directions, one being at an obtuse angle indicated by the arrow *a* and the other being an acute angle indicated by the arrow *b*. The spray in the direction

of the arrow *a* impinges, as shown in Figure 3, against the front faces of the sheets as they confront the rotor of the hammer mill. The water thus supplied to the front faces of the sheets completes the work of soaking and softening the sheets so that they may be reduced by the action of the hammer mill rotor into a pulp suspension. The water emanating from the spray pipe 94 in the direction of the arrow *b* simply serves the function of a vehicle or carrier to promote a washing of the disintegrated or slushed pulp upwardly past the two breaker plates into the hammer mill casing. Inasmuch as most of the water is supplied to the machine by way of the spray pipe 94, it is desirable that the volume of water delivered through this pipe be subject to easy control, as this means that the consistency of the pulp suspension delivered by the machine may be kept at a desired value that can be realized irrespective of the rate of feed of sheets by the conveyors. Accordingly, means are provided to vary the size of the spray openings in the pipe 94. As best shown in Figures 10 and 11, the spray pipe 94 comprises a perforated outer pipe 95 within which is journaled for rotation an inner pipe 96 having perforations which may be brought in registry to a greater or less degree with the corresponding perforations in the pipe 95. Rotation of the inner pipe 96 to effect the desired valve action is realized by a shaft 97 whose inner end portion 98 is a tongue element keyed into a corresponding slot at one end of the pipe 96. The shaft 97 is journaled for rotation in a bearing member 99 bolted to the end of the pipe 95 and passes out through the side wall 52 of the housing by way of a bearing member 100 suitably secured to such side wall. The outer end portion of the shaft 97 has affixed thereto a handle 101 which may be manipulated by the operator to effect the desired degree of registry of the openings in the pipes 95 and 96. The handle 101 preferably has a pin 102 affixed thereto and passing through an arcuate guide slot in a member 103 to which the handle may be secured by means of a winged nut 104 in threaded engagement with that portion of the pin 102 projecting beyond the outer surface of the member 103. Accordingly, when the handle 101 has been moved to a position consonant with the desired volumetric delivery of water through the spray pipe 94, it may be fixed in position until a change in the volumetric delivery of water through such spray pipe is desired. From the construction of the spray pipe 94 thus far described, it will be seen that one end of this spray pipe is supported by the shaft 97. The other end of the spray pipe is fastened to a coupling 105 which couples such spray pipe to a dead-end pipe portion 106 passing through a journal 107 secured to the side wall of the housing 52 in the same way as the journal 108. A removable cap 108 serves to close off the pipe 106, the cap being removed when clogging occurs in the spray pipe 94 so as to necessitate its cleaning.

The water delivered by way of the pipe 86 into the trough 71 accumulates as a pool or pocket in such trough. There is a tendency for chunks or undisintegrated portions of the sheets to accumulate just beyond the shelf 37. These chunks tend to fall into the trough 71 and, under the soaking action of the water present therein, disintegrates so that the rotor of the hammer mill can sweep the resulting stock upwardly past the breaker plates into the hammer mill casing. The trough 71 also serves the function of a trap, re-

taining wire, tramp iron, or similar adventitious material that gets into the hammer mill and, unless removed, might cause undue wear or injury to the hammers, discharge section, or other hammer mill parts. The undesirable accumulations in the trough 71 may be removed by opening a door or cover 109 with which it is provided, as best shown in Figure 4. The rotor of the hammer mill is constructed generally as described in the patent to which reference has already been made, but there are features of novelty therein to which attention will be directed. As shown in Figure 12, the rotor comprises end plates 110 equipped with trunnions 111 which pass through suitable bearings 112 on each side of the hammer mill housing. One of the trunnions is shown provided with a key slot 113 for receiving the key of a pulley by which the rotor may be driven from a motor or other suitable source of power. Assembled in between the end plates 110 of the rotor are a succession of arms 9, these arms being keyed to the rotor shaft 114, as best shown in Figure 4. Each two adjacent arms are, as best shown in Figure 4, arranged at right angles to each other and serve as means for supporting the hammer elements 8 of the rotor. The hammer elements, only a few of which are shown in Figure 12, are pivotally mounted on a rod 115 which passes through the aligned arms near each outer edge of such arms, there being a hammer element between each such pair of aligned arms. There are hence four such rods 115 for the entire rotor. Each rod 115 enters partly into an opening formed in each end plate 110, the opening being clear through the end plate and being tapered at its extremity so that a tapered plug 116 may be fitted therewith for preventing lateral movement of the rod 115 and the hammers mounted thereon. Access to the plug 116 for its removal may be had through an opening 117 in the side wall 52 of the hammer mill housing, when it is desired to renew the hammers. The opening 117, which is normally plugged, is in line with the circumference of the circle generated by the plug 116, so that by bringing the plug 116 in alignment with the opening 117 it is possible to remove quickly the plug 116, the rod 115, and the series of hammer elements mounted thereon. Located in between a plurality of arms 9, say, between groups of seven, are disks 118 which extend beyond the ends of the arms and which serve to keep the sheets of pulp as they are presented to the rotor from falling into the hammer mill casing. These disks are keyed to the shaft 114, as are the arms, and are locked as a solid assembly with the arms by a plurality of rods 119 having threaded ends passing through the end plates 110 and secured thereto by nuts 120. Aside from the function of the disks 118 in keeping the sheets from falling into the hammer mill, they serve the function of gripping each sheet as it presents itself to the hammer mill rotor and feeding it past the breaker plates where disintegration occurs so that feeding of the stock into the hammer mill can ensue. To this end, each disk 118 has affixed thereto a pointed or toothed element 121 which protrudes beyond the edge of the disks so that it can dig into the face of a sheet presented to the disks and carry it upwardly against the breaker plates. In this connection, it is to be observed that the hammer elements 8 project only slightly beyond the edges of the disks 118 and that, as they strike the front sheet, tend to recede inwardly so as to permit

the pointed elements 121 to grip the front sheet and carry it upwardly against the breaker plates. Once the hammer elements have moved out of contact with the front sheet of the bales, they 5 again swing outwardly beyond the edges of the disks 118 to effect the desired disintegrating action on the chunks of pulp near the breaker plates and the desired brushing action on the stock that has entered into the hammer mill casing and 10 is being carried past the ribbed lining 49 of the section 48. The slushed stock is discharged through the foraminous section 60 into a tank 122 from which it may be removed by a centrifugal pump 123 and delivered to a jordan, beater, 15 or directly to the paper-making machine vat, if desired.

A preferred arrangement of hammers and disks for the hammer mill rotor is illustrated in Figure 13 as a development of the arrangement. It will be observed that according to the arrangement the hammers 8 are staggered throughout the rotor periphery in such a way as to ensure contact of the hammers with substantially all the stock axially of the hammer mill in a single revolution of the rotor.

We claim:

1. The combination with a rotary hammer mill having an intake opening on one side into which bales of pulp sheets may be progressively fed and 30 having discharge openings on its opposite side, and means for wetting down said bales with water at said intake opening, of a primary endless conveyor having a smooth supporting surface on which said bales may be placed, and a 35 secondary endless conveyor having a spiked supporting surface onto which said bales are fed by said primary conveyor and which discharges said bales into said intake opening, both said conveyors being arranged end to end and at an angle 40 to the horizontal with the receiving end of the secondary conveyor slightly lower than the discharge end of the primary conveyor.

2. The combination with a rotary hammer mill having an intake opening on one side into which bales of pulp sheets may be progressively fed and 45 having discharge openings on its opposite side, and means for wetting down said bales with water at said intake opening, of a primary endless conveyor having a smooth supporting surface on which said bales may be placed, a secondary endless conveyor having a spiked supporting surface onto which said bales are fed by said primary conveyor and which discharges 50 said bales into said intake opening, both said conveyors being arranged end to end and at an angle to the horizontal with the receiving end of the secondary conveyor slightly lower than the discharge end of the primary conveyor, and means for moving said primary conveyor at a 55 rate of speed greater than that of the secondary conveyor.

3. The combination with a rotary hammer mill having an intake opening on one side into which bales of pulp sheets may be progressively fed and 60 having discharge openings on its opposite side, and means for wetting said bales with water at said intake opening, of a primary endless conveyor having a smooth upper surface on which said bales may be placed, guide rails at the sides of said conveyor converging toward the discharge end of said conveyor, a secondary endless conveyor having a spiked supporting surface onto which said bales are fed by said primary conveyor and which discharges said bales into said 65 intake opening, partitions at the sides of said

secondary conveyor for guiding said bales in alignment into said intake opening, both said conveyors being arranged end to end and at an angle to the horizontal with the receiving end of the secondary conveyor slightly lower than the discharge end of the primary conveyor, and means for moving said primary conveyor at a rate of speed greater than that of the secondary conveyor.

4. The combination with a rotary hammer mill 10 having an intake opening on one side into which bales of pulp sheets may be progressively fed and having discharge openings on its opposite side, and means for wetting down said bales with water at said intake opening, of a primary endless conveyor having a smooth upper surface on which said bales may be placed, a secondary 15 endless conveyor having a spiked supporting surface onto which said bales are fed by said primary conveyor and which discharges said bales 20 into said intake opening, partitions at the sides of said secondary conveyor for guiding said bales in alignment into said intake opening, both said conveyors being arranged end to end and at an angle to the horizontal with the receiving end 25 of the secondary conveyor slightly lower than the discharge end of the primary conveyor, means for moving said primary conveyor at a rate of speed greater than that of the secondary conveyor, and means manually operative from 30 outside said partitions for holding back the pulp sheets at said intake opening upon stoppage of said conveyors.

5. The combination with a rotary hammer mill 35 equipped with a hammer-carrying rotor and a casing for said rotor having an intake opening on one side into which bales of pulp sheets may be progressively fed in upstanding relationship and having discharge openings on its opposite side, of a primary breaker plate defining the top of 40 said intake opening and projecting toward the the rotor, a secondary breaker plate spaced beyond said primary one and projecting toward the rotor, and water-spraying means located between said plates and capable of delivering a water 45 spray onto said rotor.

6. The combination with a rotary hammer mill equipped with a hammer-carrying rotor and a casing for said rotor having an intake opening on one side into which bales of pulp 50 sheets may be progressively fed in upstanding relationship and having discharge openings on its opposite side, of a shelf defining the bottom of said intake opening on which said bales are supported, water-spraying means located in said 55 casing inwardly beyond and below said shelf and capable of delivering a water spray against the front face of said bales, a trough located inwardly beyond and below said water-spraying means, and means for delivering water into said 60 trough.

7. The combination with a rotary hammer mill equipped with a hammer-carrying rotor and a casing for said rotor having an intake opening on one side into which bales of pulp sheets may 65 be progressively fed in upstanding relationship and having discharge openings on its opposite side, of a shelf defining the bottom of said intake opening on which said bales are supported, water-spraying means located in said casing in- 70 wardly beyond and below said shelf and capable of delivering a water spray against the front face of said bales, said water-spraying means comprising a perforated outer tube and a perforated inner tube, and means on the out- 75

side of said casing for causing the rotation of said inner tube to bring its perforations into greater or less registry with the perforations in said outer tube.

- 5 8. A rotary hammer mill equipped with a hammer-carrying rotor and a casing for said rotor having an intake opening on one side into which bales of pulp sheets may be progressively fed and having discharge openings on its opposite side, said rotor comprising end plates, a succession of arms, a rod passing through said arms, hammer elements pivotally mounted on said rod in between said arms, said rod entering part way into openings formed through said end plates, plugs fitted into said end-plate openings and holding said rod and the hammer elements mounted thereon against end movement, each side of said casing having an opening therethrough in alignment with the circumference of 10 the circle generated by said rod upon the rotation of said rotor, and a removable closure for said last-named opening.
9. A rotary hammer mill equipped with a hammer-carrying rotor and a casing for said rotor having an intake opening on one side into which bales of pulp sheets may be progressively fed in 15 upstanding relationship and having discharge openings on its opposite side, said rotor comprising a succession of arms, a rod passing through said arms, hammer elements pivotally mounted on said rod in between said arms, a series of disks in between groups of said arms and hammers, said hammers projecting only slightly beyond the edges of said disks, and 20 pointed elements projecting beyond the edges of said disks and being adapted to grip the sheets presented to said rotor so as to carry them 25 into the casing.

10. A rotary hammer mill equipped with a hammer-carrying rotor and a sectional casing for said rotor having an intake opening on one side into which bales of pulp sheets may be progressively fed and having discharge openings 5 on its opposite side, said sectional casing comprising a top brushing plate, a foraminous discharge plate furnishing said discharge openings and arranged adjacent to said brushing plate, ledges projecting inwardly from the side walls of 10 said casing and on which both said plates are supported, and means for clamping said plates in position against said ledges.

11. A rotary hammer mill equipped with a hammer-carrying rotor and a sectional casing 15 for said rotor having an intake opening on one side into which bales of pulp sheets may be progressively fed and having discharge openings on its opposite side, said sectional casing comprising a top brushing plate, a foraminous 20 discharge plate furnishing said discharge openings and arranged adjacent to said brushing plate, ledges projecting inwardly from the side walls of said casing and on which both said plates are supported, means for clamping said 25 plates in position against said ledges, housing above said top plate and in back of said discharge plate, means operative outside of said housing for actuating said clamping means into clamping and non-clamping positions, openings 30 through said housing through which said plates may be removed, and removable closures for said last-named openings.
